FIG. 2.

Peter J. Wreisner

Inventor

By *Geo. P. Kimmel.*

Attorney

UNITED STATES PATENT OFFICE.

PETER J. WREISNER, OF DASSEL, MINNESOTA.

SWING.

1,308,568.

Specification of Letters Patent.

Patented July 1, 1919.

Application filed May 24, 1917. Serial No. 170,683.

To all whom it may concern:

Be it known that I, PETER J. WREISNER, a citizen of the United States, and resident of Dassel, in the county of Meeker and State of Minnesota, have invented certain new and useful Improvements in Swings, of which the following is a specification.

This invention relates to swings and has more especial reference to an improved self 10 propelled swing.

The invention has for its dominant object to provide a swing including a plurality of seats which are rotated by means of novel manually operated clutch mechanism about 15 a common center; the swing being easily rotated, thus, rendering the same especially desirable for use by children.

It is a more specific object of the invention to provide a novel form of clutch mechanism whereby the various seats of the swing can be collectively rotated by the occupants thereof.

Among other aims and other objects of the invention may be recited, the provision 25 of a swing of the character mentioned with a view to compactness, and in which the number of parts are few, the construction simple, the cost of production small, and efficiency and operation high.

Other improvements and novel details in the construction and arrangement of the various parts of the swing will be brought out more in detail in the description to follow, which, for a clear understanding of the 35 invention, should be considered in connection with the accompanying drawings forming a part hereof, and wherein is disclosed for the purpose of illustration a convenient and satisfactory embodiment of the invention.

In the drawings:

Figure 1 is a side elevation of my improved swing;

Fig. 2 is a fragmentary horizontal section 45 taken therethrough; and

Fig. 3 is a detail in perspective of one of the clutch mechanism operating levers.

Similar characters of reference are employed in all of the above described views 50 to indicate corresponding parts.

Referring now more specifically to the drawings, 1 designates the base of the swing including a plurality of radially disposed legs having their adjacent ends connected by 55 braces 2 and a drum 3 secured above the same through the medium of screws or other

similar fastenings generally indicated by the numeral 4. A sleeve having a closed bottom is arranged centrally of the various legs 1 and, as will be subsequently obvious, serves 60 as the pivot for the swing structure herein-after more specifically described.

A cross arm 5 having a pivot pin or pintle arranged through its middle is rotatably mounted upon the swing base, the said pivot 65 pin, which is indicated by the numeral 6, being loosely received within the sleeve secured to the adjacent inner ends of the base legs 1. If desired, the pivot sleeve may be filled with oil or other suitable lubricant 70 for an obvious purpose. Diagonally disposed bracing bars 7 are secured to the lower portion of the pivot pin 6 and to those portions of the cross arm 5 adjacent their outer extremities, thus, serving to prevent sagging 75 or breaking of the cross arm 5 when abnormal stress or strain is imparted thereto.

Bearing openings are formed transversely of the opposite ends of the cross arm 5 and have arranged adjacent thereto brackets 8, 80 the intermediate portions of which are offset whereby operating levers 9 also carrying bearing brackets 10 having intermediate offset portions may be pivoted thereto by means of pivot pins 11 passing through the said 85 transverse bearing openings. Obviously, the off-set bearing brackets 10 as carried by the several operating levers 9 are passed about the opposite sides of the cross arm 5 and also receive the adjacent ends of the several 90 bearing pins 11 therethrough, thus, materially bracing the structure against undue lateral movement.

A flexible clutch band 12 is loosely arranged about the periphery of the immovable drum 3 and has its opposite ends secured to a fulcrum lever 13 in spaced relation, the outer end of the said fulcrum lever being pivotally engaged by a connecting rod 14, the free end of which is similarly 100 engaged with the lower end of one of the operating levers 9, as at 15. A second connecting rod 16 is provided and has its respective ends pivotally engaged with the upper and lower ends of the several operating levers 9. Thus, when operating the swing, the levers 9 will be moved collectively.

Fixedly mounted upon the extreme outer ends of the cross arm 5 are seats 17 having foot rests 18 suspended therefrom through the medium of metal straps 19,

whereby the children or other users of the swing may brace themselves during the pushing and pulling of the several operating levers 9.

- 5 In operation, when either of the levers 9 is rocked, the rod 14 will be moved to actuate lever 13 and draw the end portion of the clutch element into overlapping relation and thus the flexible clutch element 12 will be in 10 engagement with the periphery of the immovable drum 3 in a manner similar to the operation of a vehicle brake band, and as a consequence, the cross arm 5 pivotally supported upon the swing base will be caused 15 to rotate about the pivot thereof. Obviously, the velocity at which the swing is rotated can be controlled by the occupants thereof through the medium of the operating levers 9.
- 20 While I have herein illustrated and described with a considerable degree of particularity the constructional details of the swing embodying my invention, it is to be understood that the invention is not limited 25 to the particular form and arrangement of the several parts which may be modified within a wide range without departing from the essence of the invention, the construction shown and the description based thereon 30 on being intended to be taken in an illustrative rather than a limiting sense.

I claim:

1. In a swing, a base having a pivot there-

on, a cross bar rotatably engaged intermediate its ends with said pivot, seats carried upon opposite end portions of said cross bar, a drum rigidly mounted on the base about said pivot, a flexible clutch band positioned about the drum, a lever having its inner end portion loosely connected with one end 40 of the clutch band, the second end portion of the band being loosely connected with the lever at a point intermediate its length, actuating levers mounted on the cross bar adjacent said seats, and a connecting rod engaged with the other end portion of the first mentioned lever and with one of the second mentioned levers.

2. In a swing, a base, a drum rigid with the base, a cross bar rotatably mounted above the drum, actuating levers pivotally connected with the cross bar, a clutch band positioned about the drum for frictional engagement with the peripheral face thereof, a lever having its inner end portion loosely connected with one end of the clutch band and having the second end portion of the clutch band loosely connected at a point intermediate its length, a rod connecting the outer end portion of the second lever with 60 one of the actuating levers, and means for imparting movement from one of said actuating levers to the other.

In testimony whereof, I affix my signature hereto.

PETER J. WREISNER.
